UNITED STATES PATENT OFFICE

WILLIAM F. POLSON, OF BUFFALO, NEW YORK

KNIFE SHARPENER

Application filed April 5, 1927. Serial No. 181,083.

My invention relates to improvements in knife sharpeners of the type having two sets or gangs of disks, marginally overlapped.

One of the objects of my invention is to provide a knife sharpener of extremely simple construction and high efficiency, and one especially adapted for household use for quickly and conveniently sharpening cutting implements.

Another object of my invention is to provide a sharpening device equipped with two sets or gangs of cutting disks centrally supported and preferably held against rotation, except under force circumferentially applied.

A further object of my invention is to provide a sharpening device of the kind mentioned in which the disks of the two sets or gangs are permanently disposed at a slight angle to each other and are so maintained, the disks being held against wobbling or tilting movement by spaced elements between which each gang is positioned.

A still further object of my invention is to provide a knife sharpener of the kind mentioned, in which the support includes two spaced parallel spindles and two spaced supporting members in which the end portions of the spindles are securely fastened, each supporting member having portions at a slight angle to each other, and two sets or gangs of marginally overlapped sharpener disks mounted on said spindles between the angularly-disposed portions of said end supporting members so that the spindles of the two sets or gangs are at slight angles and clamped between the angularly-disposed portions of said supporting members so as to be held against rotation on said spindles, except under the application of pressure applied thereto circumferentially for the purpose of presenting new portions of the cutting edges to a knife or other blade to be sharpened.

The advantages and details of construction by means of which these objects are attained will be described hereinafter.

My invention consists in the novel features of construction and in the arrangement and combination of parts to be hereinafter de-

scribed and more particularly pointed out in the subjoined claims.

In the drawings:—

Fig. 1 is a side elevation of the device.

Fig. 2 is a cross section taken on line 2—2, 55 Fig. 1.

Fig. 3 is a plan view of the device, a portion of the handle being broken away.

Fig. 4 is a detached perspective view of the frame or body portion of the device. 60

Fig. 5 is a longitudinal section taken on line 5—5, Fig. 3.

Fig. 6 is an enlarged horizontal section taken on line 6—6, Fig. 1.

Fig. 7 is an enlarged section taken on line 7—7, Fig. 5, the section being through one of the supporting members of the device and through portions of two sharpening disks showing the manner in which said disks are rotatably but non-tiltably mounted. 70

Reference being had to the drawings in detail, the numeral 8 designates the frame or support of the device, 9 and 10 the two sets or gangs of sharpening elements in the form of disks, and 11 the handle. The frame or support of the device is preferably constructed of a single piece of sheet metal bent to provide a flat bottom 12, opposite upstanding sides 13, 14, which may also be referred to as supporting members, utilized for a purpose to appear hereinafter, inwardly and upwardly inclined supporting arms 15, 16 extending, respectively, from the inner ends of said supporting members, and overlapping extensions 17, 18 on said supporting arms disposed in opposite directions so as to overlap and contact with each other, said extensions having aligned openings 19 through which a securing screw 20 is passed which is threaded axially into the handle 11. The upstanding sides or supporting members 13 and 14 are provided midway between their ends with notches 21, and at opposite sides and spaced from said notches, each supporting member has spindle openings 22, 23, formed therein, the spindle openings 22 being axially aligned and the spindle openings 23 being disposed in a like manner. The supporting members serve as end supports for two spaced parallel spindles 24, 25. Said sup-

100

porting members are made slightly angular, and more particularly describing the same, one of said supporting members is inclined inwardly from opposite ends while the other 5 is inclined outwardly from opposite ends, this being accomplished by means of a die or dies applied to said members to force one inwardly at a point centrally between its ends while maintaining the ends in fixed position, 10 and to force the other outwardly at a point midway between its ends, also while maintaining the ends of the same in fixed position. In this manner the openings formed in said end supports at opposite sides of the 15 frame or support are maintained in alignment so that when placing the spindles 24 and 25 within the frame of the device, they will be positioned in parallelism. It is particularly to be pointed out that the upper 20 portions only of the supporting members are inclined while the lower portions adjacent the bottom 12 of the frame are substantially parallel, as clearly shown in Fig. 3.

It is of course understood that before positioning the spindles within the aligned openings 22 of the supporting members, the two sets or gangs of sharpener disks 9 and 10 are mounted thereon, and after placing the spindles with their supported sharpener disks in 25 position, the ends of the spindles are headed in any suitable manner, as at 26.

The sharpener disks illustrated have their marginal portions overlapped, as at 27, which is permitted by reason of the fact that spacing elements 28 are utilized to separate the 30 marginal portions of the disks of each set or gang from each other, and while I have shown the spacing elements formed integral with the sharpener disks, it will be apparent that separate washers may be interposed between said disks in a manner now commonly employed in knife sharpeners of the multiple disk type.

In the drawings, the spacing elements are 35 formed by pressing the central portion of each sharpener disk outwardly from one side thereof, forming thereon a substantially central spacing boss. The disks are reversed in opposite sets or gangs and the marginal portions of each set or gang overlaps the marginal portions of the other in transverse alignment with the notches 21 formed in the frame or support, thus forming a substantially V-shaped blade-receiving space 29 in 40 line with said notches into which space the knife blade or other implement to be sharpened is adapted to be placed in contact with the disks.

These sharpener disks have openings 45 formed centrally therein through which the spindles 24 and 25 are passed, and these openings are a trifle larger in diameter than the diameter of said spindles so that when positioned between the sides of the frame 50 they are clamped therebetween upon head-

ing the ends of the spindles, and thus held against wobbling or tilting movement on the spindles, due to the fact that the corners 31, formed by the walls of the openings in the sharpener disks joining the inner sides 70 of the spacing bosses are in firm contact with the spindles on which they are mounted, while the corners 32 of said walls joining the outer sides of said spacing bosses are in firm contact with said spindles at diagonally opposite points. While the supporting members of the frame serve to prevent wobbling or tilting of the disks on their supporting spindles, the fact that these disks have firm support on the spindles also prevents wobbling or tilting movement. 75

It is, of course, understood that the sharpener disks are rotatable on the spindles under stress applied circumferentially so that different points of the marginal portions of the 80 disks can be brought to the cutting plane or bight of the V-shaped blade-receiving space 29 formed by the overlapping disks. It is also apparent that by reason of these disks having the walls of their central openings 90 bearing against the spindles at diagonally opposite points, and also by reason of the fact that the disks are positioned between the supporting members of the frame without play and the upper portions of said supporting members are inclined outwardly 95 from their ends at one side and inwardly at the other, that said sharpener disks of the two sets or gangs are disposed at a slight angle to each other, with the result that the peripheral edges of one set or gang of disks are disposed at a slight angle to the peripheral edges of the other set or gang, and when positioning the blade of a knife in the bight of the V-shaped blade-receiving space and 100 drawing said blade lengthwise in one direction, the corners formed by the peripheral edges and the receding sides of the cutting disks act against the knife blade to sharpen the same, the sharpening corner of all the 105 disks being in effective operation under such conditions and preventing the formation of irregularities otherwise caused by removing somewhat larger portions of the knife blade along certain parts thereof than would be 110 removed along other parts.

While the sharpening disks are rotatable upon their spindles they are not freely rotatable, although under the principle involved, with exact workmanship, said sharpener disks can be made to rotate freely and still be non-wobbling or non-tiltably arranged. However, as a knife sharpener of this type is adapted for household use and must therefore be produced at a small cost, 115 I prefer to so construct the device that the cutting disks are rotatable only when applying stress or force thereto circumferentially.

The essence of this invention resides in disposing the sharpening disks in marginally 120

overlapped sets or gangs arranged at a slight angle to each other, and in maintaining the angular disposition thereof; and to accomplish this in which I consider the preferred arrangement it is only necessary to force out or advance the upper portion of one of the upstanding sides or supporting members centrally between its ends and force inwardly or cause the other upstanding side or supporting member to recede at a point centrally between its ends, so that one-half the length of each upstanding side or supporting member is at a slight angle to the other half along its upper portion, each inclined portion of one upstanding side or supporting member being parallel with the corresponding portion of the other upstanding side or supporting member.

It is highly essential that the degree of overlap of the two sets or gangs of disks along the bight of the V-shaped blade-receiving space 29 shall be alike from one side of the device to the other, or more particularly from one end of the two sets or gangs of disks to the other end thereof, and for this reason the spindles 24, 25 should be arranged in parallelism and provision made for allowing the cutting disks to be angularly disposed upon the spindles while maintained against wobbling or tilting movement.

Having thus described my invention, what I claim is:—

1. A knife sharpener, comprising a support, a pair of spaced parallel spindles carried by said support, a set of sharpening disks on each spindle marginally overlapping the set on the other spindle, and means embodied in the construction of the knife sharpener to permanently hold the set of disks on one spindle in angular relation to the set on the other, said disks being rotatable and non-tiltable on said spindles.

2. A knife sharpener, comprising a frame having two spaced supporting members, one of said supporting members having its inner surface receding toward a point centrally between its ends and the other supporting member having its inner surface advanced from its end toward a point centrally between its ends, parallel spindles secured in said supporting members in spaced relation, and a set of sharpening disks mounted on each spindle and clamped between the receding and advancing surfaces of said side members, the two sets of disks being marginally-overlapped with their peripheral edges at acute angles to a knife blade being sharpened.

3. A knife sharpener, comprising a frame having spaced supporting walls, one of said walls receding along a portion of its height from each end thereof to a point centrally between its ends and the other being advanced along a portion of its height from opposite ends thereof to a point centrally between its ends, parallel spindles supported by said

spaced supporting walls, and two sets of marginally-spaced sharpening disks on said spindles confined against tilting movement on said spindles by said supporting walls, the marginal portions of each set of sharpening disks overlapping the marginal portions of the other set and the disks of one set being at a slight angle to the disks of the other.

4. A knife sharpener, comprising a frame having spaced supporting members, parallel disk-supporting spindles extending through the space between said supporting members and carried by the latter, and a set of rotatably-adjustable disks on each spindle having the disks of each set correspondingly tilted on their supporting spindle and so maintained by said supporting members and the disks of each set marginally overlapping those of the other, said spaced supporting members lying in contact with the end disks of each set and being angularly disposed with reference to said spindles to maintain the disks of both sets in their tilted positions.

5. A knife sharpener having a supporting frame, spaced parallel spindles carried by said frame, disks on said spindles having openings of a diameter slightly larger than the diameter of said spindles to permit of tilting the disks on said spindles, and means embodied in the construction of said supporting frame to position and maintain said disks in tilted position.

In testimony whereof I affix my signature.
